US0D1112719S

(12) **United States Design Patent** (10) **Patent No.:** **US D1,112,719 S**
(45) **Date of Patent:** **** Feb. 10, 2026**

(54) **FRAME**

(71) Applicant: **DCSTAR INC**, New York, NY (US)

(72) Inventor: **Ligui He**, New York, NY (US)

(73) Assignee: **DCSTAR INC**, New York, NY (US)

(**) Term: **15 Years**

(21) Appl. No.: **29/981,812**

(22) Filed: **Jan. 2, 2025**

Related U.S. Application Data

(63) Continuation of application No. 29/884,038, filed on Feb. 7, 2023, now Pat. No. Des. 1,064,256.

(30) **Foreign Application Priority Data**

Aug. 9, 2022 (CN) 202230517158.1

(51) **LOC (15) Cl.** **29-02**

(52) **U.S. Cl.**

USPC **D24/110.1; D24/110.4**

(57) **CLAIM**

The ornamental design for a frame, as shown and described.

DESCRIPTION

FIG. 1 is a front view of a frame showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a rear perspective view thereof.

The broken lines depict portions of the frame that form no part of the claimed design.

1 Claim, 8 Drawing Sheets
